UNITED STATES PATENT OFFICE.

MILTON E. HANSON, OF POUGHKEEPSIE, NEW YORK, ASSIGNOR TO NEWTON D. BAKER, SECRETARY OF WAR, TRUSTEE.

MANDREL FOR FORMING RECEPTACLES FROM FIBROUS MATERIAL.

1,358,635.

Specification of Letters Patent.

Patented Nov. 9, 1920.

Application filed February 21, 1920. Serial No. 360,428.

(FILED UNDER THE ACT OF MARCH 3, 1883, 22 STAT. L., 625.)

To all whom it may concern:

Be it known that I, MILTON E. HANSON, a citizen of the United States, residing in Poughkeepsie, New York, have invented Improvements in Mandrels for Forming Receptacles from Fibrous Material, of which the following is a specification.

The invention described herein may be used by the Government, or any of its officers or employees, in prosecution of work for the Government; or by any other person in the United States, without payment of any royalty thereon.

This invention relates to devices for forming receptacles of fibrous material and more specifically vessels capable of serving as air, gas or smoke filters. These filters may be used for removing dust, smoke, solid particles, bacteria, steam and toxic substances from air which becomes highly purified after passing through the same.

Among the objects of this invention is to provide a device whereby the fibrous material will be formed upon a cage having a shape conforming to the interior of the receptacle which it is desired to make.

A further object of this invention is to provide means whereby the felt may be relieved of the water contained therein by means of suction, the suction also serving to compress and pack the fibers closer together.

A more specific object of this invention is to provide a mandrel with a perforated tube substantially centrally located, this perforated tube having vanes radiating therefrom, the vanes serving to provide separate compartments between the perforated tube and a perforated cage fitting over the frame, the vanes also serving to direct the water within the mandrel cage toward the central perforated tube as the mandrel is revolved around its horizontal axis, thus permitting the water to be sucked out through the perforations of the central tube.

A still further object of this invention is to provide a device for forming receptacles of fibrous material which is cheap to manufacture, durable, of simple construction, easy to operate and possessing a high efficiency.

Reference is to be had to the accompanying drawing in which Figure 1 is a longitudinal view, partly in section, of the preferred type of mandrel frame, a part of the device being broken away to show more clearly the interior perforated core.

Fig. 2 is an end view of this mandrel frame.

Fig. 3 is a longitudinal view of the mandrel, having the perforated cage attached to the frame, which is a different modification 60 from that shown in Fig. 1. In this view a portion of the cage is broken away to show the construction of the mandrel frame.

Fig. 4 is an end view of the device shown in Fig. 3.

Figs. 5 and 6 show in a diagrammatic manner the two types of mandrel frame in operating positions.

Referring to Fig. 1, there is shown a perforated tube (1) of thin metal soldered into 70 a pipe nipple (2) which screws into a cap (3), said cap being also threaded at (4) so as to permit its attachment to a source of suction. It should be understood that the perforated tube, nipple and cap can be made 75 integral instead of in sections as shown. Around pipe nipple (2) there is mounted a box affair or housing (5) which is fashioned to take the shape of the inside of the filter. The nipple runs substantially through the 80 center of this box. On the perforated metal tube (1) there are mounted metal sheets or vanes (6) and the structure formed by these also conforms to the shape of the box (5). These vanes are radial and longitudinal, 85 while the vanes (7), in the modification shown in Fig. 3 are circumferential. The tube (1) may have its end (8) perforated, as shown in Fig. (2).

Fig. 3 shows the cage (9) placed over the 90 structure formed by the perforated tube (1) and vanes (7). This cage consists of a metal can having the bottom and wall perforated and having near its open end a flange (10), said flange serving as a stop against which 95 the fibrous material can settle and thus produce a square edge all around the mouth of the receptacle formed on the portion (9) of this cage. The extension (11) above the flange (10) is not perforated, and when 100 the cage is in position, this portion (11) fits over the box (5). In order to make the structure air-tight, and to permit the use of suction, an elastic band (12) is used to close the joint between the cage and box 105 (5). In both modifications the vanes serve also as guides and braces for the cage.

When cage (9) is placed over a structure, such as shown in Fig. 1, the vanes (6) radiating longitudinally from the perforated 110

tube (1) and reaching the wall of the cage will form separate compartments (13) (illustrated in Fig. 5). When this mandrel is in use it is placed in the furnish with the 5 water line reaching above the axis of the mandrel, as shown in Fig. 5. As the mandrel revolves, and suction is applied through the central perforated tube (1), the felt will collect upon the outside of the cage and 10 gradually build up. The suction serves to relieve the felt of its water and also to pack the fibers of the felt together. The vanes (6) serve as channels for any water which may be drawn through the perforated cage 15 and felt formed thereon and the water from one of these channels or compartments is not permitted to reach any of the other compartments. As the mandrel revolves this water within the individual compartments 20 will gradually work toward the central perforated tube and be sucked out therefrom.

In the modification shown in Fig. (3), wherein circumferential vanes are used, the 25 water (14) collects in a pocket in the manner shown in Fig. 6 and cannot be as effectively withdrawn from the felt as by the use of the radial, longitudinal vanes.

After the desired thickness of the receptacle is attained, the water is sucked out 30 therefrom and the receptacle removed from the cage.

The present invention is not limited to the specific details set forth in the foregoing examples which should be construed as 35 illustrative and not by way of limitation, and in view of the numerous modifications which may be effected therein without departing from the spirit and scope of this 40 invention it is desired that only such limitations be imposed as are indicated in the appended claims.

I claim as my invention:

1. A mandrel for making receptacles from 45 fibrous material comprising a frame having an inner core formed of perforated sheet material, a perforated cage fitting over and

detachable from said frame and vanes upon said core extending to the walls of said cage, said vanes serving as guides and braces for 50 the perforated cage.

2. A mandrel for making receptacles from fibrous material comprising a conduit having one part perforated and the other part terminating in a cap, vanes upon the perforated portion of said conduit and a detachable cage having perforated bottom and wall fitting upon said conduit and vanes. 55

3. A mandrel for making receptacles from fibrous material comprising a frame having 60 a conduit with one part thereof perforated and the other part extending through a housing and fitting into a cap, vanes upon said perforated portion of said conduit and a detachable perforated cage fitting over 65 said conduit and to said housing.

4. A mandrel for making receptacles from fibrous material comprising a frame having 70 an inner core formed of perforated sheet material, a perforated cage fitting over and detachable from said frame and longitudinal, radial vanes upon said core extending to the walls of said cage, said longitudinal, radial vanes serving as guides and braces for the perforated cage and forming separate 75 compartments from each other.

5. A mandrel for making receptacles from fibrous material comprising a conduit having one part perforated and the other part terminating in a cap, longitudinal, radial 80 vanes upon the perforated portion of said conduit and a detachable cage having perforated bottom and wall fitting upon said conduit and vanes.

6. A mandrel for making receptacles from 85 fibrous material comprising a frame having a conduit with one part thereof perforated and the other part extending through a housing and fitting into a cap, longitudinal, radial vanes upon said perforated portion 90 of said conduit and a detachable perforated cage fitting over said perforated conduit and to said housing.

MILTON E. HANSON.
